H. H. HORNSBY,
FLUID PRESSURE SYSTEM.
APPLICATION FILED APR. 20, 1916.

1,220,336.

Patented Mar. 27, 1917.

UNITED STATES PATENT OFFICE.

HARRY H. HORNSBY, OF CHICAGO, ILLINOIS.

FLUID-PRESSURE SYSTEM.

1,220,336.

Specification of Letters Patent.

Patented Mar. 27, 1917.

Application filed April 20, 1916. Serial No. 92,382.

To all whom it may concern:

Be it known that I, HARRY H. HORNSBY, a citizen of the United States, and a resident of the city of Chicago, county of Cook, and State of Illinois, have invented certain new and useful Improvements in Fluid-Pressure Systems, of which the following is a specification.

My invention relates to improvements in fluid pressure systems especially adapted for use in the brakes of street railway cars, steam cars and other compressed air systems, the present invention being an improvement on that set forth in prior patent issued jointly to Edward W. Anger and myself on February 8, 1916, No. 1,171,014, for safety means for preventing and removing ice and other obstructions in fluid-pressure systems.

The construction set forth in said prior patent is evidently satisfactory under certain conditions of use and is highly useful under all conditions, but I have found that under certain conditions of use, said prior construction is somewhat wasteful of the agent employed for preventing accumulations of ice, frost, oil, grease or gum, and the removal thereof. It appears that when pressure in the system is largely reduced for a material length of time such as when the system is "bled," or when the variations in pressure are sudden and continued, as when the motorman "fans" or rapidly operates his control valve, there is likely to be an over supply of the agent injected into the system. One object of the present invention is to so operate said system as to prevent the waste of the agent under these or analogous circumstances.

I have also discovered that it is desirable to provide a certain body of air in the upper portion of the reservoir or receptacle containing the agent, as this materially assists in starting the operation of the device, and a further object of the invention is to provide means for insuring the presence of such a body of air and preventing overfilling of the reservoir.

A further object of the invention is to provide means whereby it may be determined whether or not there is a reasonable supply of the agent present therein at any time.

A further object of the invention is to provide means for preventing clogging of the system by solid or other clogging matter.

With these objects in view, my invention

consists in the method of procedure and the combination and arrangements of parts hereinafter described and claimed.

The invention will be best understood by reference to the accompanying drawings forming a part of this specification, and in which,

Figure 1 is a side view of a device embodying my invention,

Fig. 2, a vertical section of the same,

Fig. 3, an enlarged detail section taken through a modified form of injector plug which may be employed in the system,

Fig. 4, a bottom plan view corresponding with Fig. 3,

Fig. 5, a detail view of another modified form of injector plug,

Fig. 6, a plan view of a valve disk employed in the construction and illustrated in Fig. 5, and

Fig. 7, a detail view of a modified form of combined strainer and valve construction which may also be employed in the system.

The form of construction illustrated in Figs. 1 and 2 comprises a suitable reservoir or receptacle 8 having an opening or passage 9 extending through the top thereof, the device being inserted in the air system by means of pipes 10 at each end of the passage 9, so that air employed in the system shall flow through said passage or opening 9 substantially as set forth in the prior patent referred to above. The top of the reservoir 8 which constitutes in effect a partition between said reservoir and the passage 9 is provided with a central opening into which is threaded a plug 12 having an opening or passage 13 extending therethrough, the lower portion of the opening 13 being enlarged and made square in form to accommodate a socket wrench. The plug 12 is also provided with an injector passage 15 extending vertically through one side thereof and an injector pipe or tube 16 is secured in the lower portion of said passage and depends into reservoir 8 to a position adjacent the bottom thereof. Another injector pipe or tube 17 extends upwardly from the top of the passage 15 into the passage 9, and a ball valve 18 is located in the passage 15 between pipes 16 and 17, as indicated. A strainer 19 in the form of a bell-shaped enlargement is secured to the lower end of pipe 16 and the open mouth thereof is covered by fine wire mesh 19', as indicated. A cleaning

plug 20 is threaded in the bottom of reservoir 8 and a filling spout 21 is secured in the side thereof adjacent the top, said spout being provided with a threaded plug 22 for opening and closing the same. The spout 5 is so arranged that when the reservoir 8 is filled therethrough, said spout will overflow before the reservoir is entirely filled, thus insuring the constant presence of a certain body of air in the upper portion of the 10 reservoir and preventing overfilling thereof. A test drain cock 23 is provided in one side of the reservoir 8 a short distance above the bottom thereof so as to permit testing of the reservoir for the presence of the agent, as 15 will be readily understood.

In operation when air is drawn through the passage 9 substantially as set forth in 20 said prior patent, and in the usual operation of the air system, the reservoir 8 is filled with a suitable agent for preventing accumulations of ice, frost, oil, grease and gum, or removing the same, such as denatured 25 alcohol as is employed in the construction set forth in said prior patent. In the normal operation of the system, when air is drawn through the passage 9, a jet of the alcohol will be projected into said passage and mixed with said air to accomplish the 30 results desired. The upward rush of the liquid through the passage 15 will carry the ball 18 with it and will close the lower end of the pipe 17 after a predetermined amount 35 of liquid has passed therethrough, so that after said predetermined quantity of liquid has passed, no further liquid can pass no matter how long an inequality of pressure exists between the air reservoir 8 and that in 40 passage 9. In this manner a substantially constant quantity of the agent will be injected into the air system at each prolonged 45 reduction of pressure in said system and irrespective of the extent of such reduction. When rapid fluctuations in the pressure in the air system are produced as in "fanning" by the motorman of a street car, the valve 18 will remain closed after the first upward 50 rush of the agent, thus preventing oversupply of the agent.

In the form of construction illustrated in 55 Figs. 3 and 4, I arrange a spring plate 24 under the lower end of the passage 13, said plate being secured to the plug 12 at the point 25 and provided with a minute opening 26 registering with passage 13. By this arrangement, under normal conditions of use, the pressure in the system, and consequently in passage 9, may readily force the plate 24 outwardly to fully open the passage 60 13 for entry of air into reservoir 8, but when the pressure in the passage 9 becomes less than the pressure in the reservoir 8, through withdrawal of air from the system, the second upward rush of air will tend 65 to close the plate 24, and permit escape of

air only through the minute opening 26 thus tending to maintain the pressure in the reservoir for a considerable time, as will be readily understood, and thus steady the operation of the device.

In the form of construction illustrated in 70 Figs. 5 and 6, a disk valve 27, provided with notches 28 in its edges, is provided in place of the ball valve 18, otherwise the construction is identical with that illustrated in 75 Figs. 1 and 2.

In the form of construction illustrated in 80 Fig. 7, a slightly different form of bell 29 is secured to the lower end of pipe 16 and a valve 30 of the same general form as said bell is arranged therein in position to close 85 the lower end of the pipe 16 at the first upward rush of liquid therethrough, such construction constituting a substitute for the valves 18 and 27, as will be readily understood. The operation of this construction is substantially identical with that already 90 described.

While I have illustrated and described 95 the preferred forms of construction and method of procedure for carrying my invention into effect, these are capable of variation and modification without departing from the spirit of the invention. I, therefore, do not wish to be limited to the precise 100 details of construction or method of procedure set forth, but desire to avail myself of such variations and modifications as come within the scope of the appended 105 claims.

Having described my invention what I 110 claim as new and desire to secure by Letters Patent is:

1. The method of preventing clogging of 115 an air system which consists in introducing thereinto substantially constant quantities of a clog-preventing agent, substantially as described.

2. The method of preventing clogging 120 of a compressed air system which consists in introducing thereinto substantially constant quantities of a clog-preventing agent under varying pressures in said system, substantially as described.

3. The method of preventing formation 125 of ice or frost in an air system which consists in introducing thereinto substantially constant quantities of a freezing-preventing agent, substantially as described.

4. The method of preventing formation 130 of ice or frost in a compressed air system which consists in introducing thereinto substantially constant quantities of a freezing-preventing agent under varying pressures in said system, substantially as described.

5. The combination with an air system, 135 of means for introducing thereinto substantially constant quantities of a clog-preventing agent, substantially as described.

6. The combination with a compressed air system, of means for introducing thereto substantially constant quantities of a clog-preventing agent under varying pressures in said system, substantially as described. 5
7. The combination with an air system, of means for introducing thereto substantially constant quantities of a freezing-preventing agent, substantially as described. 10
8. The combination with a compressed air system, of means for introducing thereto substantially constant quantities of a freezing-preventing agent under varying pressures in said system, substantially as described. 15
9. The combination with a compressed air system, of means operable through variations in pressure for introducing thereto substantially constant quantities of a clog-preventing agent under varying pressures in said system, substantially as described. 20
10. The combination with a compressed air system of means operable through variations in pressure for introducing thereto substantially constant quantities of a freezing-preventing agent under varying pressures in said system, substantially as described. 25
11. The combination with an air system, of a reservoir in open but restricted communication therewith, there being also an injector passage leading into said system; and means operable by flow of fluid from said reservoir into said system through said passage for checking said flow, substantially as described. 30
12. The combination with an air system, of a reservoir in open but restricted communication therewith, there being also an injector passage leading into said system; and a valve in said passage operable by flow of fluid from said reservoir into said system through said passage for checking said flow, substantially as described. 35
13. The combination with an air system, of a reservoir in open but restricted communication therewith, there being also an injector passage leading into said system; means operable by flow of fluid from said reservoir into said system through said passage for checking said flow; and strainer means preventing entry of solid particles to said passage, substantially as described. 40
14. The combination with an air system, of a reservoir in open but restricted communication therewith, there being also an injector passage leading into said system; a valve in said passage operable by flow of fluid from said reservoir into said system through said passage for checking said flow; and strainer means preventing entry of solid particles to said passage, substantially as described. 45
15. The combination with an air system, of a reservoir in open but restricted communication therewith, there being also an injector passage leading into said system; means reducing said communication when air is passing from the reservoir into the system but enlarging the communication when air is passing from the system into the reservoir; and means operable by flow of fluid from said reservoir into said system through said passage for checking said flow, substantially as described. 50
16. The combination with an air system, of a reservoir in open but restricted communication therewith, there being also an injector passage leading into said system; means reducing said communication when air is passing from the reservoir into the system but enlarging the communication when air is passing from the system into the reservoir; and a valve in said passage operable by flow of fluid from said reservoir into said system through said passage for checking said flow, substantially as described. 55
17. The combination with an air system, of a reservoir in open but restricted communication therewith, there being also an injector passage leading into said system; means reducing said communication when air is passing from the reservoir into the system but enlarging the communication when air is passing from the system into the reservoir; means operable by flow of fluid from said reservoir into said system through said passage for checking said flow; and strainer means preventing entry of solid particles to said passage, substantially as described. 60
18. The combination with an air system, of a reservoir in open but restricted communication therewith, there being also an injector passage leading into said system; means reducing said communication when air is passing from the reservoir into the system but enlarging the communication when air is passing from the system into the reservoir; a valve in said passage operable by flow of fluid from said reservoir into said system through said passage for checking said flow; and strainer means preventing entry of solid particles to said passage, substantially as described. 65
19. The combination with an air system, of a reservoir provided with an opening extending through the top thereof, said system being connected in opposite ends of said opening, there being a partition between said opening and the interior of said reservoir; a plug threaded in said partition but provided with a restricted opening extending therethrough and connecting said reservoir with said system; a spring plate secured to said plug over the lower end of the opening therethrough, said plate being provided with a minute opening registering with the open- 70

ing through the plug; an injector passage extending through said plug; an injector pipe secured in said passage and depending in said reservoir; a strainer over the lower 5 end of said pipe; a second injector pipe extending from the upper end of said injector passage into the system opening; and a valve located in said injector passage between said pipes, substantially as described.

10 20. The combination with an air system, of a reservoir in open but restricted communication therewith, there being also an injector passage leading into said system; means operable by flow of fluid from said reservoir into said system through said passage for checking said flow; and filling means for said reservoir having an overflow below the level of the top of said reservoir, substantially as described.

15 21. The combination with an air system, of a reservoir in open but restricted communication therewith, there being also an injector passage leading into said system; means operable by flow of fluid from said

reservoir into said system through said passage for checking said flow; and a test drain cock communicating with said reservoir above the bottom thereof, substantially as described.

25 22. The combination with an air system, of a reservoir in open but restricted communication therewith, there being also an injector passage leading into said system; means operable by flow of fluid from said reservoir into said system through said 30 passage for checking said flow; filling means for said reservoir having an overflow below the level of the top of said reservoir; and a test drain cock communicating with said reservoir above the bottom thereof, substantially 35 as described.

In testimony whereof I have signed my name to this specification in the presence of two subscribing witnesses.

HARRY H. HORNSBY.
